(57) CLAIM

The ornamental design for a wedge-shaped seating cushion, as shown and described.

DESCRIPTION

FIG. 1 is a top perspective view of a wedge-shaped seating cushion;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof, the left side being a mirror image thereof; and,

FIG. 8 is a cross-sectional view thereof, taken along section line 8-8 of FIG. 3.1 Claim, 6 Drawing Sheets---
